(57) **CLAIM**

The ornamental design for a screwdriver bit as shown and described.

DESCRIPTION

FIG. 1 is a left side perspective view of the first embodiment of the screwdriver bit;

FIG. 2 is a front side elevational view of the screwdriver bit of FIG. 1, the back side elevational view being a mirror image thereof;

FIG. 3 is a top plan view of the screwdriver bit of FIG. 1, the bottom plan view being a mirror image thereof;

FIG. 4 is a left end elevational view of the screwdriver bit of FIG. 1;

FIG. 5 is right end elevational view of the screwdriver bit of FIG. 1;

FIG. 6 is a left side perspective view of the second embodiment of the screwdriver bit;

FIG. 7 is a front side elevational view of the screwdriver bit of FIG. 6, the back side elevational view being a mirror image thereof;

FIG. 8 is a top plan view of the screwdriver bit of FIG. 6, the bottom plan view being a mirror image thereof;

FIG. 9 is a left end elevational view of the screwdriver bit of FIG. 6;

FIG. 10 is a right end elevational view of the screwdriver bit of FIG. 6;

FIG. 11 is a left side perspective view of the third embodiment of the screwdriver bit;

FIG. 12 is a front side elevational view of the screwdriver bit of FIG. 11, the back side elevational view being a mirror image thereof;

FIG. 13 is a top plan view of the screwdriver bit of FIG. 11, the bottom plan view being a mirror image thereof;

FIG. 14 is a left end elevational view of the screwdriver bit of FIG. 11;

FIG. 15 is a right end elevational view of the screwdriver bit of FIG. 11;

FIG. 16 is a left side perspective view of the fourth embodiment of the screwdriver bit;

FIG. 17 is a front side elevational view of the screwdriver bit of FIG. 16, the back side elevational view being a mirror image thereof;

FIG. 18 is a top plan view of the screwdriver bit of FIG. 16, the bottom plan view being a mirror image thereof;

FIG. 19 is a left end elevational view of the screwdriver bit of FIG. 16;

FIG. 20 is a right end elevational view of the screwdriver bit of FIG. 16;

FIG. 21 is a left side perspective view of the fifth embodiment of the screwdriver bit;

(Continued)

FIG. 22 is a front side elevational view of the screwdriver bit of FIG. 21, the back side elevational view being a mirror image thereof;
 FIG. 23 is a top plan view of the screwdriver bit of FIG. 21, the bottom plan view being a mirror image thereof;
 FIG. 24 is a left end elevational view of the screwdriver bit of FIG. 21;
 FIG. 25 is a right end elevational view of the screwdriver bit of FIG. 21;
 FIG. 26 is a left side perspective view of the sixth embodiment of the screwdriver bit;
 FIG. 27 is a front side elevational view of the screwdriver bit of FIG. 26, the back side elevational view being a mirror image thereof;
 FIG. 28 is a top plan view of the screwdriver bit of FIG. 26, the bottom plan view being a mirror image thereof;
 FIG. 29 is a left end elevational view of the screwdriver bit of FIG. 26; and,
 FIG. 30 is a right end elevational view of the screwdriver bit of FIG. 26.
